UNITED STATES PATENT OFFICE.

SHUBAEL COTTLE, OF NEW YORK, N. Y.

DESIGN FOR CHAIN FABRIC.

SPECIFICATION forming part of Design No. 35,057, dated September 10, 1901.

Application filed May 21, 1901. Serial No. 61,811. Term of patent 7 years.

To all whom it may concern:

Be it known that I, SHUBAEL COTTLE, a citizen of the United States of America, and a resident of New York, in the county and State of New York, have invented and produced a new and original design for a Chain Fabric, of which the following is a specification.

Reference should be had to the accompanying drawings, forming part of this specification.

Figure 1 is a plan view of a chain fabric showing my new design. Fig. 2 is a perspective view of a portion of the same chain fabric, on a greatly enlarged scale, to show the appearance when viewed obliquely.

As shown in the drawings, the leading or material feature of my design consists of a series of U-shaped links A. The said links are flat and perforated on the sides at B. The curved portion of each link passes through the perforations B in the contiguous arms of adjacent U-shaped links A. In the usual natural condition of the chain fabric the ends of the U-shaped links are either in contact in pairs or very close together, whereby the

general appearance is that of close and partially overlapping parallel rows of U's with their sides near one another. The drawings serve to show the appearance more clearly 30 than can ever be explained. When the chain fabric is looked at from the side, as apparent from Fig. 2, the appearance is that of letter "O's" located upon the top of each other and partially overlapping. On the upper edge of 35 the chain fabric may be seen little rings linked upon the free ends of the U-shaped links.

It is apparent that this chain fabric is applicable to the construction of purses, bags, 40 and other similar articles.

Having described my invention, what I claim as new, and desire to secure by Letters Patent, is—

The design for a chain fabric, substantially 45~ as herein shown and described.

In testimony whereof I have hereunto subscribed my name this 18th day of May, 1901.

SHUBAEL COTTLE. [L. S.]
